UNITED STATES PATENT OFFICE.

JULIUS LAMBERT, OF HOBOKEN, NEW JERSEY.

DESIGN FOR THE ORNAMENTATION OF POCKET-BOOK CLASPS, &c.

SPECIFICATION forming part of Design No. 17,324, dated May 10, 1887.

Application filed March 10, 1887. Serial No. 230,472. Term of patent 7 years.

To all whom it may concern:

Be it known that I, JULIUS LAMBERT, a citizen of the United States, residing at Hoboken, in the county of Hudson and State of New Jersey, have invented and produced a new and original Design for Clasps for Pocket-Books and Similar Articles, of which the following is a specification.

The object of this design is to provide a novel ornamentation for the clasps of pocket books and other articles.

The design is illustrated by the accompanying photograph.

On the left of the picture is a figure of a man facing a figure of a bear. The bear is in upright position and supports an object—such as a log or a similar appearing object—by his fore paws. A tree or shrub having leaves is shown in proximity to said man and bear.

20 Birds are perched on the shrub or tree.

The letter A indicates the man, B the bear, C the shrub or tree, D the leaves, and E the birds.

Near the bear B is an object such as a rod, 25 staff, or sword, F. On the right of the picture is a figure of a man, G, facing a bear, H, the bear being in an upright position. The bear supports an object—such as a loaf or a similar appearing object—by his fore paws. Near the 30 last-named man and bear is a tree or shrub, I, bearing leaves, and a man or a figure, K, is lying on the ground near the last-named man and bear.

At the upper part of the picture is a panel for an inscription. Above said panel are 35 leaves L and birds M, inclosed in a suitable border, O.

What I claim as new, and desire to secure by Letters Patent, is—

1. The design for ornamenting clasps for 40 pocket-books and other articles herein shown and described, the same consisting of the upright figures of the men, A G, and the bears, B H, said bears supporting objects in their fore paws, the trees or shrubs C I, placed near said 45 men and bears, and a prostrate figure, K, near one of said men and bears, the whole being surmounted by a panel for an inscription.

2. The design for ornamenting clasps for 50 pocket-books and other articles herein shown and described, the same consisting of the upright figures of the men, A G, and the bears, B H, said bears supporting objects in their fore paws, the trees or shrubs C I, placed near 55 said men and bears, and a prostrate figure, K, near one of said men and bears, the whole being surmounted by a panel for an inscription and by leaves and birds.

In testimony whereof I have hereunto set my hand and seal in the presence of two subscribing witnesses.

JULIUS LAMBERT. [I. S.]
